UNITED STATES PATENT OFFICE.

ELASHA DEAN CULLISON, OF CHICAGO, ILLINOIS.

RADIATOR CAP.

Application filed April 26, 1922. Serial No. 556,777.

To all whom it may concern:

Be it known that I, ELASHA D. CULLISON, a citizen of the United States, residing at Chicago, in the county of Cook and State 5 of Illinois, have invented a new and useful Radiator Cap, of which the following is a specification.

This invention relates to a cap for radiators, one of the objects of the invention 10 being to provide a cap which will be held yieldingly on its seat so as to completely close the filling opening, the pressure of the cap upon the seat being adjustable readily.

A further object is to provide a radiator 15 cap which can be quickly shifted away from its seat so as to give convenient access to the opening.

Another object is to provide a structure of 20 this character the springs of which are housed and thus protected.

It is a well known fact that the ordinary screw cap used on automobile radiators is not satisfactory because the threads become mutilated, considerable time is required to 25 screw or unscrew the cap, the cap is usually so hot that it cannot be comfortably handled, and it is easy to lose the cap.

The present invention is designed to overcome all of the foregoing disadvantages and 30 provides a very simple and inexpensive but efficient structure which can be applied readily.

With the foregoing and other objects in view which will appear as the description 35 proceeds, the invention resides in the combination and arrangement of parts and in the details of construction hereinafter described and claimed, it being understood that, within the scope of what is claimed, 40 changes in the precise embodiment of the invention shown can be made without departing from the spirit of the invention.

In the accompanying drawings the preferred form of the invention has been shown.

In said drawings—

Figure 1 is a side elevation of the cap in position on the filling neck or collar of a radiator, the position of the cap when open being indicated by dotted lines.

Figure 2 is a section on line 2—2, Figure 1.

Referring to the figures by characters of reference 1 designates the usual filling neck or collar of a radiator, the same being provided, in the present instance, with a V-shaped bearing edge 2 forming a seat for

the cap constituting the present invention. It is to be understood, however, that this bearing edge can be of any other desired shape.

Secured in the neck or collar 1 at diametrically opposed points are anchoring screws or studs 3 each of which is engaged by an eye 4 formed at one end of a rod 5. Each rod is slidably mounted within a sleeve 6 closed at its lower end, as shown at 60 7 while the upper portion thereof is externally screw threaded as indicated at 8. The two sleeves 6 extend through and are adjustably mounted within ears 9 extending in opposite directions from a cap 10. A groove 11 is formed in the bottom face of the cap and adapted to receive the edge 2 of the neck or collar 1.

Seated within each of the sleeves 6 is 75 a coiled spring 12 extending around the rod 5 therein. One end of the spring bears against the closed end of the sleeve while the other end is restrained by a nut 13 threaded on the rod 5. Thus by adjusting so the nut the compression of the spring can be varied and the cap caused to bear on the edge 2 with any desired pressure. The sleeves 6 are threaded into and extend downwardly from the end portions of a tubular 85 handle 14 open at its ends and bearing at its center on the cap 10.

The springs 12 are normally under compression and, consequently, hold the cap to its seat. When it is desired to shift the 90 cap so as to give access to the neck or collar 1 the handle 14 is pulled upwardly to raise the cap and cause the sleeves 6 to slide on the rods 5. Thus the springs 12 will be placed under further compression but sufficient clearance will be provided to enable the cap to be swung laterally and downwardly relative to the neck or collar and to a position such as indicated, for example, by dotted lines in Figure 1. The tubular handle 14 is kept cool because air is free to circulate therethrough and, therefore, the cap can be handled without causing discomfort. When it is desired to replace the cap on its seat it is merely necessary to 100 reverse the foregoing operation.

While the device has been described as particularly useful in connection with radiators, it is to be understood that it can be employed wherever it is desired to use a 110 sealing cap capable of being quickly placed in or removed from position.

What is claimed is:—

1. The combination with a neck providing a seat, of a cap, sleeves adjustably mounted in the cap, yieldingly restrained 5 elements slideable in the sleeves and pivotally anchored to the neck, and a handle engaged and held by the sleeves.

2. The combination with a neck providing a seat, of a cap normally bearing on 10 the seat, sleeves adjustably mounted in opposed portions of the cap, members slideable within the sleeves and pivotally anchored

to the neck, springs within the sleeves, means adjustably engaging said members for regulating the compression of the springs, and 15 a handle engaged and held by the sleeves.

In testimony that I claim the foregoing as my own, I have hereto affixed my signature in the presence of two witnesses.

ELASHA DEAN CULLISON.
